SUCTION PRODUCING MUFFLER

Erwin C. Horton, Hamburg, N. Y., assignor to
Trico Products Corporation, Buffalo, N. Y.

Application September 5, 1933. Serial No. 688,219

5 Claims. (Cl. 181—44)

This invention relates to motor vehicles and internal combustion engines and particularly to an apparatus having the combined effect of muffling the exhaust from the vehicle, or internal combustion engine, and of providing a source of suction or less than atmospheric pressure for operating pumps, horns, windshield cleaners, or other devices such as those which may be associated with the vehicle or engine.

In general the present invention contemplates, in apparatus wherein the flow of gases expelled from the engine through a muffling zone is caused to create a zone of sub-atmospheric pressure for the purposes indicated above or otherwise, the provision of means for eliminating excessive back pressures in the engine exhaust passage, such means including an automatic control mechanism adapted to function under the varying conditions of engine operation. For example, when the engine is operating at low speed or under light load, the contemplated means will be automatically adjusted to utilize the kinetic energy of a large portion of the flowing exhaust gases for the production and maintenance of the zone of sub-atmospheric pressure; and when the engine is operating at high speed or under great load and is exhausting relatively large quantities of gases, such as would tend to create excessive "back pressure" or pressure between the engine and the suction producing apparatus and also create an excessive degree of suction, the means contemplated will automatically effect a by-passage of a considerable portion of the exhaust gases into the atmosphere, to thereby maintain the suction and back pressure at substantially constant degrees. The means for governing the automatic control are constructed and arranged in such manner as to be unaffected by the heat of the exhaust gases, which heat may vary in temperature and quantity in accordance with operating conditions of the engine, such as load, speed and other factors.

These and other objects and advantages, including those inherent in the various features of arrangement and formation of parts, will become apparent from the following description of the one typical embodiment of the invention that is illustrated in the accompanying drawing, wherein:

Fig. 1 is a longitudinal section through the apparatus;

Fig. 2 is a transverse section, being taken substantially along line 2—2 of Fig. 1;

Fig. 3 is a transverse section, being taken substantially along line 3—3 of Fig. 1; and

Figs. 4 and 5 are fragmentary longitudinal sec-

tional views taken respectively through portions of the apparatus which appear in elevation in Fig. 1.

As shown in Fig. 1, the apparatus includes a casting comprising an elongated tubular member 11, 5 a closure member 12 for one end of member 11 and provided with a nipple 13 for attachment to a conduit 14 extending and connected to the engine exhaust passage or exhaust manifold, and a closure member 15 for the opposite end of tubular 10 member 11. Closure member 15 has an opening 16 which may open directly into the atmosphere, or, as illustrated, may be provided with a nipple 17 for connection to a conduit 18 leading to the atmosphere. 15

Extending transversely of and within tube 11, in spaced relation to closure 12, and preferably secured to the walls of member 11, is a wall 19 having opening 21 in substantial alignment with nipple 13, and having plural perforations 22 for 20 passing fluid from the inlet opening (nipple 13) side of wall 19, designated inlet chamber 20, to the other side of the wall, designated chamber 23. Another transverse wall, 24, spaced from closure 15 serves with the latter and member 11 to form 25 outlet chamber 25. Wall 24 has an opening 26 aligned with opening 21 in wall 19, and also has an opening 27 in substantial alignment with apertures 22 of wall 19.

A Venturi tube connects chambers 20 and 25, 30 and comprises a tubular member 28 secured to wall 19 over opening 21 and a second tubular member, 29, secured to wall 24 and extending through opening 26 thereof into chamber 25. Tube 28 is relatively wide at its inlet end (the end 35 secured to wall 19), and has its walls converging toward the opposite end to provide restricted throat 31. Tube 29, connecting throat 31 has walls diverging toward closure 15, in such manner that the Venturi tube is of constantly increasing 40 diameter from throat 31 to the terminal portion in chamber 25. The terminal portion 32 of the inlet end of tube 29 is bevelled and contacts with a medial portion of tube 28 to define an annular chamber 33 about throat 31, the walls of which 45 have plural openings 34 into chamber 33. Secured to wall portion 32 of chamber 33 and to tube 11 is a nipple 35 adapted for connection to a suction conduit 36 which may extend to a horn, pump, windshield cleaner, or other device operable 50 by or utilizing sub-atmospheric pressure.

Secured to wall 24 over opening 27 is one end of tubular member 37 which extends into chamber 25. The walls of chamber 37 have perforations or apertures 38 and the end 39 thereof is 55

adjacent to flanged plate 41. Confined between wall 24 and plate 41 is a helical or coiled spring 42, the convolutions of which are closed or in contact when plate 41 is positioned adjacent tube 5 end 39. The ends of the spring are respectively secured to wall 24 and the plate, so that when the latter is moved away from tube end 39, the convolutions of the spring will be separated, thereby providing an opening between chambers 23 and 10 25, via tube 37, perforations 38 and the interstices between the spring convolutions.

Closure plate 41 is carried for movement toward and from tube end 39 by a rod 43 which extends axially through the perforated tube, 15 through a guiding opening in wall 19, and through a bearing plug 44, the latter being seated in an aperture in closure 12. The forward end, 45, of the rod is connected to one end of a coiled spring 47, the opposite end of the spring being attached 20 to member 48 which is threaded to, and hence is adjustable longitudinally of, a tube 49 which projects forwardly from the casing over the plug 48.

In operation, when the engine is operating at 25 relatively low speeds or under light loads, so that the quantity of exhaust gases is small, the gases will pass from conduit 14, through chamber 26, through the Venturi sections 28 and 29 into chamber 25, and thence to the atmosphere via discharge opening 16. Due to the small quantity of 30 fluid passing the apparatus, the restriction provided by Venturi throat 32 will be insufficient to cause pressure to build up in chamber 26 in such excessive degree as to appreciably impede engine operation. Accordingly, since a small pressure 35 (above atmospheric pressure) is effective in chambers 20 and 23, the closure 41 will be held seated by spring 47 and hence no fluid will pass from chambers 20 or 23 into chamber 25 except through the venturi. The term "seated" has reference 40 to closed position of convolutions of spring 42 since it is not essential that closure 41 actually contact tube 37.

Fluid passing through the Venturi tube will 45 move at maximum velocity through the throat 31, thereby having static pressure at this point of considerably less than atmospheric. Hence fluid will be withdrawn from annular chamber 33 through apertures 34, all in accordance with the well known "Venturi" action, so that chamber 33 50 will be a zone of fluid under subatmospheric pressure, and fluid will flow into same through the conduit 36 to withdraw air or other fluid from the device to which the conduit is attached.

As engine speed or load is increased, with 55 resultant increase in the quantity of exhaust gases, excessive pressures would tend to develop in chambers 20 and 23. However, upon the initiation of any such increase of pressure, the closure 41 60 will be unseated to spread the convolutions of spring 42, and thereby provide a by-passage about the Venturi tube from chamber 20 to chamber 25, via apertures 22 in wall 19, chamber 23, apertured tube 37 and the interstices between the 65 convolutions of spring 42.

The volumetric flow capacity of the by-pass will 70 increase as the volume of exhaust gases per unit of time increases, since the convolutions of spring 42 will open in proportion to pressure increase in chambers 20 and 23. Hence, when the engine is operating at high speed and under heavy load, a greater portion of the exhaust gases may pass 75 through the by-passage than through the Venturi tube, and, accordingly, the automatic control thus provided will tend to stabilize the flow of gases

through the venturi and the degree of suction in chamber 33.

The spring 42 will be necessarily somewhat resilient, and may be designed so as to tend to either open or close under its own resiliency. It is preferred, however, that spring 42 be subservient in its action to the spring 48, which is positioned out of the path of the exhaust gases and hence will not be subject to such excessive temperatures as might destroy its temper. By this arrangement 10 the device will function in like manner whether the gases be cool or excessively hot. The tension of spring 48 may be varied, to vary the degree of suction or the maximum pressure in chamber 20, by adjusting the threaded spring retainer 48. 15

The muffling action of the device is effected by the expansion of gases in the Venturi tube and by the breaking up and expansion of gases in passing the apertures 22, 38 and the interstices between the convolutions of spring 42. It will be understood 20 that other muffling instrumentalities may be added to the device if desired.

When the engine is operating, the flow gases entering the muffler will be of pulsating character, the number of pulsations per unit of time depending, of course, on the number of engine cylinders and engine speed. The resultant periodic increase and decrease in the volume and pressure of gases entering the muffler will cause the valve means 41, 42 to periodically open and close. It 30 has been found that at high engine speeds, where the periods of pulsation are very rapid and of short duration, the inertia of the valve means will prevent complete closing at each pulsation, and that the valve will have relatively small 35 movement, although sufficient to produce an appreciable muffling action. At low engine speeds, without the Venturi means, the valve means 41, 42 would tend to open and close with each pulsation of the exhaust gases, which action is attended with more or less noise and wear upon the parts. 40

However, as illustrated in Fig. 1, the constricted throat 31 of the venturi is of diameter approximately one fourth that of the exhaust conduit 45 14, and due to the sub-atmospheric pressure maintaining in the throat, it has been found that the flow capacity of the venturi is approximately four times that of a straight tube of like diameter. Therefore, with the relative proportions 50 illustrated, the Venturi tube can pass about one fourth of the maximum total volume of fluid entering from conduit 14, without unduly increasing the engine back pressure. Accordingly, when the engine is operating at relatively 55 low speeds, the venturi will accommodate a large portion, if not all, of the gases entering the muffler during each pulsation, and thus modify the extent of the pulsations which would otherwise impinge upon the valve means 41, 42. In this 60 manner the muffling effect of the device is greatly facilitated.

It will be understood, however, that the proportions indicated above should be varied in accordance with variations in the type of engine, 65 engine speed, and the inertia of the valve means in the muffler, so that, at such speeds of the engine as would enable the valve means 41, 42 to substantially close between exhaust gas pulsations, the venturi will have sufficient capacity 70 to pass substantially the entire quantity of gases exhausted from the engine.

It will be understood further that the device herein illustrated and described is merely one typical embodiment of the inventive principles 75

involved, which may be embodied in devices having other structural characteristics, without departing from the scope of this invention.

What is claimed is:

5. 1. In a muffler, a casing having opposite end walls with an inlet port and an outlet port respectively, wall means separating the casing interior into an inlet chamber adjacent the inlet port and an outlet chamber adjacent the outlet port, said wall means having an opening therethrough, valve means for normally closing said opening, said valve means including a rod extending through the end wall having the inlet port and through said opening and being movable toward the end wall having the outlet port upon opening of the valve means, resilient means disposed outside of said casing for exerting a valve closing pressure upon said rod, and means for varying such pressure of said resilient means.
10. 2. In a muffler, a casing having inlet and outlet chambers respectively having an inlet and an outlet port, a wall between said chambers having an opening, a tube secured to the wall over said opening and having the secured end thereof communicating with the inlet chamber and having apertures in the walls thereof opening into said outlet chamber, a plate adjacent the other end of said tube mounted for movement toward and away from the tube, a helical member overlying said tube and having one end secured to said wall and the other end secured to said plate, the helical member being flexible whereby the convolutions thereof may be disposed close together or may be separated to admit of the passage of fluid therebetween, a rod extending through one end wall of said casing and having one end secured to said plate, resilient means disposed outside of the casing exerting pressure upon the rod for urging the plate to a position wherein the convolutions of the helical member are close together, and means for varying the pressure exerted upon the rod by the resilient means.
15. 4. A muffler comprising a casing having a pair of branch passages for exhaust gases, one of said passages being a tube within the casing and having a fixed orifice of restricted area, and the other passage being defined by said tube and the casing walls and being yieldably closed by valve means, said valve means comprising a coil of wire so formed that adjacent convolutions thereof will close against each other to restrict fluid passage therebetween or open away from each other to facilitate such fluid passage, resilient means for urging said adjacent convolutions to close against each other, and fluid pressure actuated means for urging the convolutions to open away from each other.
20. 5. In a muffler, a casing having an inlet opening adjacent one end thereof and an outlet opening adjacent the opposite end thereof, a perforated wall adjacent the inlet end and a second wall adjacent the outlet end, a Venturi tube with a suction take-off at the restricted portion thereof, said tube extending within said casing between said walls and having its inlet end opening into the chamber between the first mentioned wall and the casing end having the inlet opening and in alignment with the latter, and said tube discharging into the chamber between said second wall and the casing end having the outlet opening, and a pressure responsive valve in the second wall for opening when the pressure in the last mentioned chamber is less by a predetermined degree than the pressure in the chamber between said walls.
25. 3. In a muffler, a casing having inlet and outlet chambers respectively having an inlet and an outlet port, a wall between said chambers having an opening, a tube secured to the wall over said opening and having the secured end thereof communicating with the inlet chamber and having apertures in the walls thereof opening into said outlet chamber, a plate adjacent the other end of said tube mounted for movement
